UNITED STATES PATENT OFFICE.

WILLIAM EARLE SHAVER, OF WELDON, ILLINOIS.

POWER APPLIANCE.

No. 806,010.

Specification of Letters Patent.

Patented Nov. 28, 1905.

Application filed April 23, 1904. Serial No. 204,633.

To all whom it may concern:

Be it known that I, WILLIAM EARLE SHAVER, a citizen of the United States, residing at Weldon, in the county of DeWitt and State of Illinois, have invented new and useful Improvements in Power Appliances, of which the following is a specification.

This invention relates to an improved power appliance, the object of the invention being 10 to provide an appliance adapted to be employed for effectively applying power for various operations.

In the accompanying drawings, Figure 1 is a sectional elevation of my improved power appliance as mounted for use as a post-extractor. Fig. 2 is a similar view taken on line 2 2 of Fig. 1. Fig. 3 is an enlarged side elevation of the head-frame, showing the windlass mechanism and gearing. Fig. 4 is a plan 20 view of the same. Fig. 5 is a sectional view of the drum of the windlass. Fig. 6 is an end view of the same, and Fig. 7 is a side view of one of the ratchet-gears.

Like reference-numerals designate corresponding parts in all the figures of the drawings.

The power appliance comprises, essentially, a head-frame 1, which is substantially rectangular, as best illustrated in Fig. 4, and 30 which may be mounted, if desired, upon any preferred type of supporting-frame. In the present instance I have shown it mounted upon legs 2, which preferably diverge from their upper toward their lower ends and consist of angle-irons, or, in other words, they are substantially L-shaped in cross-section, the upper ends thereof being bolted, riveted, or otherwise secured to the head-frame, as shown at 3. To the lower ends of the legs are connected feet or base-irons 4, consisting of angle-plates having flat bottoms 5, which rest directly on the ground and sustain the structure as a whole in a vertical position. At opposite sides the head-frame is provided with 40 bearings 6 for the reception of a removable through bolt, rod, or shaft 7, which is insertable and withdrawable by endwise movement through the bearings 6, held in place by suitable fasteners 8, which may either consist 45 of cotter-pins, as shown, nuts, or their equivalent, the said fasteners being inserted through openings in the ends of said bolt, rod, or shaft outside of or beyond the bearings. Surrounding the shaft 7 is a peripheral and spirally-grooved drum 9, upon the reduced ends 55 of which are placed ratchet-gears 11, the

ends of the drum being squared, as shown, to fit correspondingly-shaped openings 12 in the ratchet-gears 11.

Associated with the shaft of the drum is a lever-socket 13, adapted to receive a lever-handle 14 of any suitable length and provided with a bifurcated terminal portion or yoke 15, the arms of which extend outside of the gears 11 and are provided with collars 16, 65 which embrace and are journaled to turn loosely on the shaft 7 just inside of the bearings 6. These collars 16 fit between the bearings and ratchet-gears 11 and hold the latter in engagement with the squared ends of the 70 drum. The yoke 15 also carries ratchet-dogs 17, which engage the gears 11 for turning the windlass-shaft, while holding bolts or detents 18 are pivotally mounted on the head-frame to engage the gears 11 and prevent backward 75 movement of the same. By this construction and arrangement of parts the shaft 7 may be withdrawn by endwise movement when the fasteners 8 are removed. Upon its withdrawal the drum 9 and yoke 15 will be disconnected from the head-frame, and as the collars 16 of the yoke no longer hold the ratchet-gears in engagement with the squared 80 ends 10 of the drum 9 said gears may be quickly and conveniently removed, whereby 85 the parts of the operating mechanism are quickly disassociated.

Secured to one end of the head-frame is a bracket 19, having an outwardly-extending centrally-arranged boss 20 with an inwardly-extending sleeve 21, in which is journaled a short counter-shaft 22, carrying an operating-crank 23 on its outer end, the hub portion of which bears against the outer end of the boss 20, the inner end of the shaft 22 being secured 95 by means of a cotter-pin 24 or its equivalent. The crank 23 is provided in the outer side of its hub portion with a diametrical notch or groove 25, in which is received a pin or key 26, which is insertable through and removable from an opening in the outer end of the counter-shaft 22, thus providing for the removal and attachment of the crank. Upon the inner end of the counter-shaft 22 is a pinion 27, which lies beneath and meshes with 100 one of the ratchet-gears 11, whereby the rotary motion imparted to the counter-shaft 22 by the crank 23 is transmitted to the drum 9, around which may be wrapped one end of a rope or cable 28, forming part of a block-and-fall mechanism. It will thus be seen that the drum may be operated either by the lever 14 105

or the crank 23, the lever working with a vibratory action and the crank with a rotary motion. By using the lever and crank simultaneously greater power may be obtained to 5 drive the drum than by the use of either alone, as the operation of the crank will continuously drive the drum, while the operation of the lever may be properly timed to secure increased power when the crank is on center. 10 Also by the use of these driving devices the drum may constantly or intermittently be revolved, as desired. The counter-shaft 22 and pinion 27 may be conveniently disconnected 15 from the head-frame by simply removing the pin 26 and sliding the shaft 22 outwardly from its bearing-sleeve 21.

In the adaptation of the machine as a post-extractor the block-and-fall mechanism, consisting of the rope or cable 28 and the pulley-blocks 29 and 30, is connected with the machine, the upper block 29 being provided with a hook 31, which engages over a portion 20 of the head-frame 1, as shown in Fig. 1. The lower block 30 is also provided with a hook 25 32, to which is attached a chain 33, which is passed around the post, (indicated at 34.) After the parts have been adjusted in the manner illustrated in Figs. 1 and 2 the lever 14 is rocked back and forth until the post is 30 loosened, after which the crank 23 may be used for more speedily elevating the loosened post.

The power appliance may be otherwise mounted and employed for imparting power 35 for lifting and unloading operations, stretching wires in the construction and repair of fences, and a variety of other uses wherever hoisting, extracting, or stretching operations are necessary.

40 Having thus described the invention, what is claimed as new is—

1. A power appliance comprising a head-frame, provided with bearings, a removable shaft mounted in said bearings and provided 45 with retaining means, a drum loose on said shaft, detachable ratchet-gears carried by said drum, a lever embodying a yoke which embraces the gears and is journaled on said shaft, operating-pawlS connected with the yoke, and 50 detents pivotally mounted on the head-frame, said pawls and detents engaging the ratchet-gears.

2. A power appliance comprising a frame provided with bearings, a removable shaft 55 mounted in said bearings and provided with retaining means, a drum loose on said shaft, ratchet-gears removably engaging the oppo-

site ends of the drum, an operating-lever provided with a yoke embracing said gears, and provided with bearing-sleeves interposed between 60 the ratchet-gears and bearings on the frame, whereby said sleeves hold the ratchet-gears in engagement with the drum, operating-pawls carried by the yoke and engaging the ratchet-gears, and detents on the head-frame also engaging the ratchet-gears, said shaft serving 65 to connect the drum, ratchet-gears and lever-yoke with the frame, whereby the removal of the shaft will disassociate said parts, substantially as described. 70

3. A combination-hoist comprising a frame, a shaft journaled therein and removable therefrom, a drum on said shaft provided with ratchet-gears, an operating-lever journaled on 75 said shaft and co-operating with said ratchet-gears, and separable auxiliary operating mechanism comprising a bracket removably applied to the frame, a counter-shaft journaled in said bracket, a pinion on said shaft meshing with one of the ratchet-gears, an operating-crank on said shaft, and detachable fasteners at opposite ends of the counter-shaft whereby the shaft is held in operative relation to the bracket and the operating-crank is retained in position on the counter-shaft. 80 85

4. A power appliance comprising a frame, a shaft removably mounted thereon, a drum carried by the shaft, ratchet-wheels removably fitted upon the ends of the drum, and a yoke-lever journaled on the shaft and provided 90 with pawls engaging the ratchet-wheels, said lever co-operating with the frame to retain the ratchet-wheels in engagement with the drum, the construction being such that the removal of the shaft effects the disassemblage 95 of the parts.

5. A power appliance comprising a frame provided with bearings, a shaft mounted in said bearings and removable endwise therefrom and provided with retaining means, a 100 drum loosely journaled upon the intermediate portion of said shaft, ratchet-wheels detachably fitted upon the ends of the drum, a yoke-lever having collars journaled on the shaft between the bearings and ratchet-wheels and 105 maintaining the latter in engagement with the ends of the drum, and pawls actuated by said lever to turn the ratchet-wheels.

In testimony whereof I affix my signature in presence of two witnesses.
